UNITED STATES PATENT OFFICE.

FLORENCE B. TRUAX, OF LINCOLN, NEBRASKA.

SURGICAL APPARATUS.

Application filed May 18, 1921. Serial No. 470,510.

To all whom it may concern:

Be it known that I, FLORENCE B. TRUAX, a citizen of the United States, and a resident of Lincoln, in the county of Lancaster and 5 State of Nebraska, have invented certain new and useful Improvements in Surgical Apparatus, of which the following is a specification.

This invention relates particularly to an 10 appliance for delivery to the body of a patient of a fluid such as saline solution now generally used by the medical profession after operative or other cases.

It is of extreme importance that this fluid 15 be delivered to the patient's body at a certain prescribed temperature. It likewise is necessary that the fluid be delivered at a comparatively slow rate which approximates forty drops per minute, this being usually 20 as much as patient's body can absorb. The delivery of a cold fluid, especially in the case of a sub-normal patient, would be dangerous inasmuch as the body does not absorb cold fluids and furthermore, they cause internal accumulations of gas in the body of 25 a patient.

It is therefore, the prime object of my invention to provide an apparatus of this general type in which suitable provision is 30 made for maintaining the saline solution or other fluid, which is to be delivered to the patient's body at a predetermined and desirable temperature.

This is accomplished by the provision of 35 a double walled receptacle which will maintain the fluid for a considerable length of time in its heated condition. The delivery tube which conducts this fluid from the receptacle to the patient's body is, in accordance 40 with my invention, made somewhat shorter than is usual in appliances of this type, the walls of this tubing being furthermore considerably thicker. The dropper bulb which is of standard form and which is interposed 45 within the delivery tube for controlling the dispensing of the fluid, is in my invention, insulated by a rubber hood or cover, thereby conserving the heat at this point, thus effecting a considerable saving of the heat of 50 the fluid and rendering this appliance considerably more efficient.

Cooperating with the short delivery tube hereinafter referred to, I provide an adjustable stand for supporting the container 55 or receptacle, which stand may be adjusted to the proper height to accommodate this

appliance to the conditions prevalent at the time of its use.

The object of this invention has been sought to be obtained by the use of thermos bottles, acting as containers and also by the use of electric heaters surrounding the delivery tube. This arrangement and many others have met with little success because they were inadaptable to the varying conditions prevailing where it was necessary to use this appliance.

As stated hereinbefore the container which forms a part of this invention is in the form of a double walled can, the space 70 between the walls thereof being preferably in the form of a vacuum. The inside of the can is straight walled, thereby permitting easy access to the inside from the opening of the can and permitting the can to be 75 quickly and easily sterilized and made ready for immediate use again.

I do not claim as my invention the dropper bulb inasmuch as the bulb illustrated in my invention is of the usual standard construction. I do, however, claim as new the arrangement wherein the fluid is retained in its heated condition, by use of an insulated receptacle and heavy walled short delivery tube, together with the adjustable rack 80 cooperating therewith. By provision of this adjustable rack or stand I am enabled to use a tube somewhat shorter than that now 85 generally employed.

The various features of my invention will 90 be made more apparent in the accompanying specification and drawings in which:

Fig. 1 is an elevation of an appliance constructed in accordance with my invention,

Fig. 2 is a sectional view of the receptacle,

Fig. 3 is a sectional view partly in elevation of the dropper and cover, and

Fig. 4 is a disassembled perspective view 100 of the bulb protecting cup.

In the drawings the appliance consists primarily of a container C, a delivery tube D, dropper bulb E, and supporting stand F.

The container C comprises substantially an outer wall 10 and an inner wall 11, which, 105 together form an open ended receptacle, the walls 10 and 11 being spaced as shown, thereby providing a hollow space 12 between the inner and outer walls of this container. This space 12 is preferably made into a vacuum 110 thereby insulating the contents of the container from without thus enabling the tem-

perature of the contents to be kept for a considerable length of time at the desired pre-determined degree. For closing the open end of the container there is a rubber cork 13 having a handle 14. This rubber cork sits on a circumferential rib 15 pressed inwardly from the inner wall 11. The walls of the container are provided adjacent the bottom with an outlet spout 16 through 10 which the fluid contained therein may pass to the delivery tube D.

The delivery tube D is preferably made of rubber and in two sections such as illustrated particularly in Fig. 1, to permit the 15 interposition of the glass dropper bulb E. As shown in Fig. 3 this bulb E has its ends 17 preferably smaller than is usual so that the ends of the delivery tube D may be forced thereon. As stated hereinbefore, the 20 walls of the delivery tube D are considerably thicker than usual thereby insulating the fluid contained therein from without. Attached to the end of the delivery tube D is a rectal tube 18 which may be of the usual 25 type and construction.

For insulating the dropper bulb E I provide a hood or cover 19 halved centrally as at 20 to enable the same to be slipped over the ends of the dropper bulb before it is positioned in the delivery tube D. This hood or cover is formed of heavy soft rubber and insulates the dropper bulb E so as to conserve the heat of the fluid contained therein.

The stand or support F comprises a base 35 21, and a pair of telescoping members 22 and 23 projecting therefrom. A set screw 24 secures the member 23 in its adjusted position with respect to the member 22. A hook 40 25 cooperates with an eye 26 formed on the container C, to attach the container to the supporting stand. A lug 27 secured to the container at its bottom also abuts the supporting stand, to assist in maintaining the container in its upright position.

45 In use the saline solution or other fluid is placed in the container C and the supporting stand properly adjusted. It is evi-

dent that by providing means adjustable in height for supporting the container C that a shorter length delivery tube D will suffice. 50 The fluid is thoroughly insulated in the container C and will be maintained at an even temperature. The delivery tube as has been stated, is formed of thick walls, while the dropper bulb E is insulated by the hood or 55 cover 19. It therefore follows that the saline solution is maintained at the proper temperature for a considerable length of time.

I reserve the right to make such changes 60 and modifications as may come within the purview of the accompanying claims.

Having thus described my invention, what I claim is:

1. An insulated surgical irrigating unit 65 of the class described comprising an insulated container, a thick walled delivery tube connected thereto, a dropper bulb connected to said tube, an insulating hood for said dropper bulb and means for supporting said 70 container.

2. A surgical appliance of the class described comprising an open ended insulated container, means for closing said container, a delivery tube connected to said container, 75 said delivery tube having comparatively thick walls, a dropper bulb connected to said tube, a rubber insulating hood covering said dropper tube and means for supporting said container.

3. A surgical appliance of the class described comprising a container, said container having spaced walls forming a vacuum therebetween, a rubber stopper closing the open end of said receptacle, said receptacle being formed with an outlet opening, a delivery tube connected to said outlet opening, the walls of said tube being comparatively thick, a dropper bulb connected to said tube, a hood for said dropper 90 bulb formed in two halves and of heavy rubber and an adjustable stand for supporting said container.

FLORENCE B. TRUAX.
